FUEL BURNING AIR HEATER WITH
UPRIGHT TUBESGeorge B. Herbster, Cleveland, Ohio, assignor to
Herbster-Schmiler, Inc., Cleveland, Ohio, a
corporation of Ohio

Application April 6, 1948, Serial No. 19,402

1 Claim. (Cl. 126—110)

1

This invention relates to circulating heaters and particularly to an upright circulating heater adapted to deliver heated air efficiently concurrently about the full extent of its horizontal periphery directly into a room or a suitable plenum chamber.

In prior circulating space heaters, the usual practise is to draw the air into the heater at one face and discharge it generally unidirectionally from another face, diffusing it to some extent by directional vanes so as to reduce hot blasts and to provide better distribution throughout the room.

In upright suspended heaters the air is usually discharged forwardly from the heater and then deflected downwardly by external vanes.

All of these prior types of heaters cause well-defined localized streams or hot blasts of air such that some portions of the room in the direct path of the discharged air are overheated whereas other portions of the room not only do not receive a sufficient amount of heated air but often are subjected to relatively cold localized return air currents.

In my U. S. Patent No. 2,336,609, issued December 14, 1943, there is disclosed an oscillating or rotating upright heater which discharges the air generally forwardly from one face through suitable directional vanes which deflect the air into a plurality of coaxial annular streams about an axis normal to the rotational axis of the heater. As a result, the air stream is not concentrated and maintained continuously in the same location and localized return currents of cold air are rendered less pronounced. However, even in this structure the occupants of the room are subjected to periodic drafts of heated air as the heater rotates or oscillates.

One of the objects of the present invention is to provide a heater which delivers heated air directly into a room more uniformly and without pronounced localized air streams or hot blasts and localized return streams of cold air.

By the present structure the heated air is delivered from the entire horizontal periphery of the heater concurrently and return air is drawn in at the top and bottom so that strong localized heated blasts of air are eliminated and replaced by a more gradual movement of the entire body of the heated air in the room away from the heater and of the return air toward the heater. As a result the heated air is delivered more directly and more uniformly to all parts of the room continuously, strong localized currents of heated air and cool return air

are eliminated, and the circulation and distribution of heated air throughout the room as a whole is more even and efficient.

Furthermore, the present structure lends itself readily to incorporation in a centralized heating unit of the duct delivery type in such manner that the direct radiation loss into the space in which the unit is located is reduced to a minimum.

Other objects and advantages will become apparent from the following description wherein reference is made to the drawings, in which:

Fig. 1 is a side elevation, partly in section, illustrating a preferred embodiment of the present heater;

Fig. 2 is a fragmentary horizontal sectional view of the heater taken on the line 2—2 of Fig. 1;

Fig. 3 is a side elevation, partly in section, illustrating the incorporation of the heater into a centralized heating unit; and,

Figs. 4 and 5 are horizontal sectional views taken on lines 4—4 and 5—5, respectively of Fig. 3.

Referring first to Fig. 1 and Fig. 2, the heater is shown for purposes of illustration as a gas fired heater, its use with other types of fuel being readily apparent from the illustrative example. The heater 1 comprises a heat exchanger, indicated generally at 2, a combustion compartment or chamber 3 arranged beneath the heat exchanger and in communication at its top with the bottom of the exchanger so as to supply heating media into the exchanger. A header 4 is arranged at the top of the exchanger and is in communication therewith for receiving the heating media or products of combustion and discharging them through a suitable stack 5.

The heat exchanger 2 comprises a plurality of upright tubes 6 arranged in an annular row about a common upright central axis and in spaced apart face to face relation to each other. The tubes are secured in this position by a suitable annular top plate 7 and annular bottom plate 8 to which they are connected by being telescopically fitted thereto at their ends, respectively, and welded in place. The combustion chamber 3 comprises an annular trough, indicated generally at 9, which is coaxial with the heat exchanger and is closed at the top by the bottom plate 8 of the exchanger so that heat media or products from the chamber 3 may pass upwardly through the tubes 6. The header 4 is in the form of an inverted annular trough,

40

45

50

indicated generally at 10, which is closed at the bottom by the top plate 7 so that the heating media or products of combustion may pass thereto and thence through the stack 5.

In the form illustrated, heat is supplied to the exchanger by a suitable gas burner 11 having an annular head with the usual upwardly directed ports for discharging a combustible mixture of gas and air upwardly toward the tubes and underside of the plate 8, the upper face of the burner being placed sufficiently below the plate 8 to prevent impingement of the flame. The burner 11 has a mixing bell 12 which extends part way along the underside of the burner head so as to deliver the mixture of primary air and gas into the burner generally tangentially thereof, thus providing a uniform distribution of the mixture throughout the head of the burner. Gas is supplied to the mixing bell of the burner through the usual nozzle 13 and pipe 14, the latter of which extends through the outer side wall of the combustion chamber 3. The lower portion of the outer wall of the combustion chamber 3 is provided with a plurality of air inlet ports 15 which are preferably distributed uniformly peripherally of the outer wall and are of adequate size to admit sufficient primary air and secondary air for sustaining combustion. Except for the ports 15 and the stack 5, the combustion chamber, heat exchanger, and header form a unit which is sealed, thus preventing any escape of combustible media and products of combustion into the air to be heated.

Mounted within the heat exchanger in coaxial relation therewith is a rotary centrifugal impeller 16 which is coextensive axially with the tubes 6. The impeller vanes or blades of the impeller 16 lie adjacent the inner peripheral limit of the row of tubes with operating clearance only. The impeller is supported on suitable bearing spiders 17 arranged one at each end of the exchanger. The upper spider 17 also supports a suitable motor 18 which is directly connected to the shaft of the impeller 16. The impeller is open at both ends so as to receive air through the central passage of the header 4 and the central passage of the combustion chamber 3.

The unit thus described may be suspended from the ceiling, or supported on a pedestal, above the normal head level of occupants of the room in either of which cases there is a free access of return air to be heated at both the upper and lower ends of the heater. When pedestal supported, a hollow pedestal can be used and arranged with ports at the bottom so that air can be drawn from the floor level for recirculation. In some instances the heater is supported on the floor in which case suitable legs 19 are provided so as to support it an adequate distance from the floor to permit a free flow of air into the central passage of the combustion chamber 3. It is desirable to provide deflecting vanes for deflecting the air downwardly and for this purpose the annular vanes 20 are provided. The vanes 20 extend entirely around the heat exchanger 2 and are mounted on a number of circumferentially spaced upright supporting rods 21 so that they can be installed or removed as a unit.

Thus the air to be heated is drawn into the impeller at both ends of the heater and is discharged concurrently about the entire peripheral extent of the heat exchanger 2. As a result the end walls and the walls of the central passages

of both the combustion chamber and the header are air washed for recuperating heat which would otherwise be radiated directly therefrom. The tubes are generally elongated in horizontal cross section so as to provide a large heat exchange surface both internally and externally, relative to their volumetric capacity so that a high efficiency exchange of heat between the heating media and the tubes and between the tubes and the outside air results.

The air discharged from a rotary centrifugal impeller is discharged with a swirling motion about the axis of the impeller and has substantial radial and tangential components. Accordingly, the tubes 6 are not arranged with the major axes of their horizontal cross sections extending tangentially or radially of the axis. Instead, each has the major axes of its horizontal cross section oblique to the radial plane from the axis of the impeller through the geometric center of the horizontal cross section, with the outer sides offset circumferentially of the axis or row in the direction of rotation of the impeller from the inner sides. Furthermore, that edge of the inner side of each tube which is leading in the direction of rotation of the impeller blades, i. e., the edge which is first to be passed by a given blade of the impeller, joins the adjacent side wall of the tube at an acute angle as indicated at 22, whereas the relatively trailing edge of the inner side i. e., the edge which is last to be passed by a given blade of the impeller is curved away from the blades and outwardly of the heat exchanger on a large radius, as indicated at 23. As a result the passages between the tubes not only are oblique to the radial planes through the axis of the impeller and more nearly aligned with the direction of discharge of the air but also are shaped so as to have as much venturi effect as possible. Thus, as illustrated in Fig. 2, the passages have a relatively short entrance portion 24 which is of decrescent width outwardly from the impeller and which connects with a longer discharge portion 25 which is of progressively increasing width from its inner end outwardly to the outer side of the tubes. This arrangement provides high efficiency of heat exchange relation and air circulation.

As mentioned, in some instances it is desirable to incorporate the heater in a centralized heating unit, particularly in those instances in which the centralized heating unit is to be installed in a room which is to be occupied and in which direct radiation from the heating unit and plenum chamber would be objectionable to the occupants of the room. Such a combination is illustrated in Figs. 3 through 5, in which the heater proper is essentially that described in Figs. 1 and 2 except that the vanes 20 are omitted. Referring to Figs. 3 through 5, the heater is indicated generally at 30. Surrounding the heat exchange portion of the heater is an air scroll or casing 31 having a spiral peripheral wall 32 coaxial with the heat exchanger and top and bottom walls 33 and 34. The walls 33 and 34 have central openings coaxial with the central passage of the heat exchanger for admitting air to the impeller. The scroll terminates in a discharge portion 35 which is connected with one or more of the usual distribution ducts. The spiral wall 31 preferably begins with a radius substantially equal to the external radius of the heat exchanger and its rate of expansion is determined so that there is a free flow of air through the exchanger and scroll without a recirculation of

the air around the periphery of the exchanger, the air circumventing only that part of the exchanger from its point of discharge between the tubes to the discharge portion 35. The heater and the scroll and a portion of the discharge portion 35 are enclosed in a suitable outer casing 37, the walls of which are spaced from the walls of the scroll so as to form an air passage 38 which completely surrounds the scroll and heater. The casing 37 is provided with an inlet passage 39 which is connected to the usual cold air return duct. Thus the entire outer surface of the scroll and heater are air washed by the cold return air so that heat that would otherwise be radiated therefrom directly into the room is recuperated and carried by the circulated air through the heat exchanger and discharged through the duct system.

In order that the forced circulation of air not interfere with the operation of the burner, a suitable duct 42 extends from the combustion chamber across the passage 38 and opens to the outside through the wall of the casing 37 for conducting outside air to the combustion chamber for sustaining combustion. The duct 42 also accommodates the usual gas feed line 43.

It is apparent from the foregoing description that the heater is adapted both for installation in a room to be heated or for incorporation in a centralized heating system and that it is effective for overcoming the objections heretofore pointed out.

Having thus described my invention, I claim:

A heater comprising a plurality of upright stationary tubes arranged in an annular row about an upright axis and in spaced apart face to face relation to each other, means providing an annular combustion chamber at the bottom

of said tubes and in communication at its top therewith, a gas burner having upwardly discharging jets arranged in said chamber, an exhaust header at the upper ends of the tubes and in communication at its bottom therewith, a rotary impeller coaxial with the row of tubes and enclosed thereby and having its outer periphery close to the inner periphery of the row of tubes, each of said tubes being elongated in horizontal cross section and having the major axis of its horizontal cross section non-radial and non-tangential with respect to the axis of the row so as to provide, between adjacent tubes, through passages each of which, as a whole, slopes from its inner to its outer end in the direction of rotation of the impeller, and adjacent surfaces of adjacent tubes being configured so that the passage between each two adjacent tubes is gradually contracted for a portion from the inner end part way toward its outer end and gradually expanded outwardly from said portion to its outer end.

GEORGE B. HERBSTER.
